UNITED STATES PATENT OFFICE.

OLIVER ROLAND INGERSOLL, OF BROOKLYN, NEW YORK.

LIFE-BOAT.

No. 328,852.

Specification of Letters Patent.

Patented Aug. 14, 1906.

Application filed September 15, 1905. Serial No. 278,641.

To all whom it may concern:

Be it known that I, OLIVER ROLAND INGERSOLL, a citizen of the United States, residing at Brooklyn, in the county of Kings and State of New York, have invented new and useful Improvements in Life-Boats, of which the following is a specification.

My present invention relates to improvements in boats of that class or style denominated "life-boats," and the objects are to provide such a boat built of metal which will be positively self-righting and self-bailing, which will have a maximum buoyancy and of great strength in resisting the exigencies of the service, and which is capable of withstanding the effects of accidental or intentional puncture by bullets or other missiles.

With these objects in view the invention consists in the novel constructions of parts and their aggroupment in operative combination, as will be hereinafter fully specified, and the asserted novelty then particularly pointed out and distinctly claimed.

I have fully and clearly illustrated the improvements in the accompanying drawings, to be taken as a part hereof, and whereof—

Figure 1 is a longitudinal vertical section through the boat, showing the air-compartments, in which are disposed metallic air-tanks, layers or blocks of cork, or other buoyant material. Fig. 2 is a top plan view of the boat in which are indicated the water-vents. Fig. 3 is a transverse vertical section through the boat, taken on the line 2 2 of Fig. 1. Fig. 4 is an end view in elevation of the boat, showing the keel-line and indicating the clamp fixed on the end of the boat. Fig. 5 is a detail perspective view of the brace or clamp which is fixed at the stem and stern-post of the boat.

The hull of the boat is composed of an inner shell of metal 1, a middle shell 2 of suitable material, and an outer layer 3 of metal, shaped substantially as indicated in the drawings and laid together in unison with both ends of like contour, and the keel-plate 4, secured longitudinally along the seam of the bottom.

5 designates the gunwales of the hull.

6 designates the upper-deck floor, and in each end portion of the boat are formed

chambers or compartments 7 8, positioned one above the other, constituting air-compartments, wherein are placed air-tanks 9, the lower of which may be utilized for general storage purposes and the upper one serving to act as air-chamber to increase buoyancy and insure the self-righting of the boat. At each end of the boat—that is, the stem and stern-posts of the boat—is secured 60 a bracket or clamp 10, known as a "ring-bolt." In the cross-plate of each of these ring-bolts is fixed an eye 11, adapted to be connected to a lifting rope when the boat is lowered or lifted in service. Seats 12 are 65 mounted across and between the gunwales substantially as shown in the drawings.

13 designates the deck, extending the length of the boat at this line, as indicated, and in the space between the deck and the 70 bottom of the boat are formed compartments 14, arranged on each side of the keelson. In these compartments are disposed metal air-tanks 15, whereby perfect buoyancy is attained. It will be perceived that some or 75 all of the compartments may be provided with layers or blocks of cork 16, which are fastened together, serving the double purpose of promoting buoyancy and of affording protection against destruction of the 80 material and liability of leakage when the cork is punctured. Passing through the lower chamber are the vertically-positioned vent-tubes 17, extending through the deck and through the bottom of the boat and 85 serve to permit the water breaking into the boat to escape into the sea. The vent-tubes 17 are formed with two annular collars or flanges 18, which engage the surfaces of the floor of the deck and the bottom of the boat, 90 and thus serve to support and strengthen those elements, substantially as shown in Fig. 3 of the drawings. Each vent-tube may be provided with a self-closing valve 19 to prevent the water from entering upwardly 95 through the bottom, while at the same time permitting it to freely escape from above. It will be observed that by the construction of these vent-tubes with double annular flanges at the ends they afford the important 100 function of grasping between the flanges the respective surfaces of the deck and those of

the bottom, thus preventing both expansion of the parts engaged and serving to strengthen the parts in relation to stiffening the boat and at the same time more effectively preventing collapse and leakage than heretofore.

The hull of the boat is strengthened by transversely-laid ribs 20 and longitudinally-secured stringers 21, as shown in Fig. 3, and 10 the ribs being indicated in Fig. 1 by dotted lines. It will be further perceived that by filling that portion of the boat below the deck with cork or other buoyant material the self-righting capacity will be increased, and at 15 the same time the boat is rendered bullet-proof to such an extent that if the cork is pierced the spongy characteristic of that material will cause the cork to close behind the missile as it progresses in its course. The 20 cork selected is preferably sheets or blocks secured together, so that almost any amount of damage to the bottom or to the deck of the boat would not materially injure its buoyancy, self-righting functions, or self-bailing 25 qualities.

Should some of the compartments of the lower deck be filled with metal air-tanks, the buoyancy of the boat would not be affected by these even should one or more of them be 30 pierced or otherwise damaged, since those remaining intact would more than counterbalance the damage arising from such as had been pierced. It may be stated that should the boat be provided with motive power one 35 or more of the tanks may be used for the storage of oil. It is also observed that boats may be constructed without a cork filling or similar buoyant placed between the deck and the bottom; but in place thereof the space 40 may be filled throughout with air-tanks made of galvanized steel, copper, or other suitable metal, so that should the bottom of the boat be pierced more or less there would be but little water-space created, and the air-tanks 45 would not be liable to receive injuries so general and extensive as to interfere in the least with the buoyancy of the boat, because the deck-floor then becomes the flotation bottom of the boat, as has been demonstrated in official 50 tests. The boat is more steady than before the punctures, and, in fact, it is impossible to capsize it.

The air-tanks are provided with the usual closures or hand-plates opening into the deck 55 of the boat designed for the storage of water and provisions, and, as a matter of fact, all the tankage mentioned could be arranged to hold provisions or water, and thus instead of the usual "four-days" supply, consisting of 60 loose cans and kegs, there would be the airtight tanks with provisions lasting thirty days, none of which could be damaged by the elements or be lost in the sea.

It will be observed that the construction and arrangement of the air-chambers at the 65 end of the boat and the air-chambers disposed in series under the deck occupy so much of the space within the shell that they cause the buoyancy of the boat to greatly exceed its loading capacity, and therefore the 70 boat is rendered self-righting when capsized and incapable of being sunk under ordinary 75 conditions.

Having thus described my invention, what I claim, and desire to secure by Letters Patent, is—

1. In a self-righting life-boat, the tanks 7 and 8 located at the bow and stern, one above the other, metallic air-tight compartments fitted to said tanks, the bottom of the 80 hull comprising an inner metallic shell and an outer metallic shell 3, and an intermediate shell 2, the keelson 4 reinforcing the said shell, a metallic deck 13 extending the length of the boat and dividing the said tanks 7 and 8, a series of chambers positioned intermediate of the tanks 8, air-tight metallic tanks disposed in said chambers, vertical vent-tubes 17 formed with two annular flanges at each end to engage the respective surfaces of 90 the deck 13, and also those of the bottom, the brackets 10 provided with the eyes 11 and secured to the bow and stern of the boat, the legs of the same extending down each side thereof, the inclined decks extending 95 from the deck 13 upwardly to the sides of the boat, and the thwarts 12 extending from side to side of the boat and above said inclined decks, the whole being so constructed that the buoyancy capacity of the boat greatly 10 exceeds the loading capacity, thereby rendering the boat self-righting when capsized and incapable of being sunk under ordinary conditions.

2. In a self-righting life-boat, the tanks 7 and 8 located at the bow and stern, one above the other, metallic air-tight compartments fitted to said tanks, the bottom of the hull comprising an inner metallic shell and an outer metallic shell 3, and an intermediate 11 shell 2, the keelson 4 reinforcing the said shell, a metallic deck 13 extending the length of the boat and dividing the said tanks 7 and 8, a series of chambers positioned intermediate of the tanks 8, air-tight metallic tanks 11 disposed in said chambers, vertical vent-tubes 17 formed with two annular flanges at each end to engage the respective surfaces of the deck 13, and also those of the bottom, the brackets 10 provided with the eyes 11 12 and secured to the bow and stern of the boat, the legs of the same extending down each side thereof, the inclined decks extending from the deck 13 upwardly to the sides of the boat, the metal cross-ribs and the longitudinal ribs constituting the frame, and the 125

thwarts 12 extending from side to side of the boat and above said inclined decks, the whole being so constructed that the buoyancy capacity of the boat greatly exceeds the loading capacity, thereby rendering the boat self-righting when capsized and incapable of being sunk under ordinary conditions.

In testimony whereof I affix my signature in presence of two subscribing witnesses.
